DESIGN FOR A PLAQUE OR SIMILAR ARTICLE

Theodore T. Oates, Lead, S. Dak.

Application December 30, 1946, Serial No. 135,847

Term of patent 7 years

(Cl. D29—23)

To all whom it may concern:

Be it known that I, Theodore T. Oates, a citizen of the United States, residing at Lead, in the county of Lawrence and State of South Dakota, have invented a new, original, and ornamental Design for a Plaque or Similar Article, of which the following is a specification, reference being had to the accompanying drawing, forming part thereof.

I claim:

The ornamental design for a plaque or similar article, substantially as shown.

THEODORE T. OATES.
